UNITED STATES PATENT OFFICE.

WILLIAM C. HIERING, OF NEWARK, NEW JERSEY, ASSIGNOR TO J. E. MERGOTT CO.,
OF NEWARK, NEW JERSEY, A CORPORATION OF DELAWARE.

SNAP CATCH FOR TRIPLE-FRAME BAGS.

Application filed May 25, 1927. Serial No. 193,966.

This invention relates to bag frame catches with special reference to compartmented bags having triple frames hingedly engaged in the usual manner.

Such bags are extensively in vogue with women for carrying toilet accessories, handkerchiefs, change purses and like impedimenta and it is regarded as advantageous to have two or more compartments independent from each other, each being accessible without in any way disturbing the contents of the other.

Difficulty is however encountered in securing the frame closures and a plurality of separate fastener elements are usually involved, bewildering to the user when determining which fastener to release in order to open the desired compartment; it is moreover unsightly and expensive to have several catches arranged on the frame and therefore it is one of the objects of the present invention to obviate these disadvantages by a combination of few and simple parts presenting a neat appearing fastener permitting either of the bag compartments to be opened without releasing the other.

This and other objects, such as economy of parts and construction, selective operation and pleasing appearance are accomplished by the novel construction and arrangement of parts hereinafter described and shown in the accompanying drawing, forming a material part of this disclosure, and in which:—

Figure 1 is a perspective view of a three part bag frame as provided with catches made in accordance with the invention.

Figure 2 is an enlarged front elevational view of catches and parts connected therewith.

Figure 3 is a transverse sectional view taken on line 3—3 of Figure 2.

As seen in the drawing the bag frame consists of three inverted U shaped similar elements designated 5, 6 and 7 respectively, all being of channel shaped cross section and connected by rivets 8 at the ends of their parallel end members, these rivets being in register and permitting the frame to freely pivot upon them.

The central element 6 carries a torsion spring 9 one end of it being bent at a right angle to make contact with the wall of the frame and the other end portion flattened to operatively engage in the bights of a pair

of loops 10, extending downward through 55 apertures in the outer wall of the channel frame 6, from the rear edge of a sheet metal box-like support 11 of oblong rectangular shape.

This support reaches outwardly at the 60 front to extend over the front frame element 5 substantially flush with its outer surface and its front edge is adapted to engage an upstanding lug 12 rigidly set in the element 5 in the manner of a snap catch, the rear 65 angle of the lug raising the support catch 11 when the two frame elements 5 and 6 are firmly pressed together until the lug has been wholly received under the catch, whereupon the torsion spring acts to maintain the 70 parts in operative engagement in a well known manner.

In order to operate the catch to release the lug a finger pad 13 is riveted or otherwise firmly fixed on top of the support catch 11, 75 the pad being generally ovoidal in contour and positioned symmetrically on the upper wall of the same, thus constituting a lever-like handle to displace the support element 11 by pressing the same rearwardly.

The pad 13 is provided with an oval aperture 14 centrally therein, the same having well rounded edges to facilitate the entry and removal of a sphere 15 rigidly carried at the ends of a spring arm 16, which latter 85 element is bifurcated and provided with brackets 17 which are rigidly fixed centrally on the outer portion of the frame element 7, this device constituting another well known form of bag or purse catch.

From the foregoing it will be seen that the compartment between the frame elements 5 and 6 is rendered accessible by pressing the pad 13 rearwardly and allowing the frame 5 to be withdrawn from contact with the frame 95 element 6.

Correspondingly, upon applying force to raise the sphere 15 and press it through the aperture 14, the compartment between the frame elements 6 and 7 becomes accessible, either being operated without in any manner disturbing or releasing the other.

Having thus described my invention, what I claim as new and desire to secure by Letters Patent, is:—

1. A bag frame having three elements pivotally connected at their ends, a lug fixed on one of the outer elements, a spring carried

sphere on the other outer element, a snap support engageable with said lug, said support being hinged on the central frame member, a torsion spring to actuate said support, 5 a pad on said support, and means in said pad to engage said sphere.

2. A bag frame having a central element and a pivoted element at each side thereof, a catch pivoted to said central element to 10 extend over one of the side elements, an apertured finger pad on said catch, spring means to retain said catch in a normal operative position, an angular lug on one of said side elements to engage said catch, and a spring 15 carried spherical member on the opposite

side element to engage in the aperture of said pad.

3. A bag frame having a central element and a pivoted element at each side thereof, a spring actuated catch provided with an aperture pivoted to said central element to extend over only one of the side elements designed to have holding engagement therewith and a spherical member on the opposite side element to engage in the aperture of the spring 20 actuated catch designed to have holding engagement therewith. 25

This specification signed this 12th day of May, 1927.

WILLIAM C. HIERING.
